UNITED STATES PATENT OFFICE.

ALBERT SNOECK, OF HARTFORD, CONNECTICUT.

VOTING-MACHINE.

SPECIFICATION forming part of Letters Patent No. 608,922, dated August 9, 1898.

Application filed August 1, 1895. Serial No. 557,807. (No model.)

To all whom it may concern:

Be it known that I, ALBERT SNOECK, a subject of the King of Belgium, but at present residing at Hartford, in the county of Hartford, State of Connecticut, have invented an Improvement in Voting-Machines, of which the following description, in connection with the accompanying drawings, is a specification, like letters and figures on the drawings representing like parts.

This invention relates to voting-machines wherein each candidate to be voted for is represented by a key which when operated registers one vote for that candidate, said machine also containing one or more straight-ticket keys operable independent of the individual registering or voting keys for the purpose of casting by a single movement one vote for all the candidates of a certain party, the machine further containing a single independent-voting device to receive a single ticket or ballot upon which are written the names of all those candidates voted for whose names do not appear adjacent the regular keys of the machine.

One object of this my present invention is to provide suitable interlocking mechanism to prevent simultaneous operation of any two or more keys in the entire machine.

I preferably employ, and this present invention comprehends, a single locking device or mechanism suitably connected with all the keys of the machine and in such manner that it will operate to prevent simultaneous operation of any two or more keys irrespective of the particular grouping or division of the keys into series to meet the requirements of different candidates or sets of candidates for the same or different offices.

I employ a single independent-voting device, as above stated, and to enable those persons who are counting the votes to know whether or not the voter casting an independent ballot containing independent or irregular names has registered votes for more than the prescribed number of candidates I provide what I term a "number-indicating device," which is operated whenever any of the individual-keys of the machine are operated, it being moved one step by the operation of each individual-key, and which when the independent-voting device is subsequently operated

registers upon the independent vote or ballot the number of votes previously registered to indicate how many the voter may yet vote for 55 on the independent ballot or, vice versa, may register upon the independent ballot the number of votes which may be cast on said independent ballot.

My invention further comprehends a visual 60 indicating device for and preferably arranged adjacent each registering-key, which upon such proper operation of the key as records a vote will be changed to such position or condition as shall indicate to the voter that the 65 vote represented by it has been registered.

In the drawings, Figure 1, in front elevation, with a part of the mechanism exposed, shows one form of voting-machine embodying my invention; Fig. 2, a rear elevation of the 70 machine shown in Fig. 1; Fig. 3, a top or plan view of the machine shown in Figs. 1 and 2; Fig. 4, an enlarged vertical section on the dotted line $x-x$, Fig. 2, showing a portion only of the machine because of the lack of space 75 on the drawings; Fig. 5, an enlarged sectional detail on the dotted line $x'-x'$, Fig. 2, showing the independent-voting mechanism; Fig. 6, a top or plan view of the parts shown in Fig. 5, the same section-line $x'-x'$ being also indicated 80 in Fig. 6; Fig. 7, a perspective detail showing two of the registering-keys; Fig. 8, a vertical section through one of the grouping devices H, the section being taken on the dotted line x^2-x^2 , Fig. 1; Figs. 9 to 14, details of 85 parts thereof to be described; Fig. 15, a perspective detail showing two of the straight-ticket keys b' , and Fig. 16 a detail to be referred to.

The machine which I have herein shown as 90 embodying my invention and which I have selected to illustrate said invention is constructed in most respects in a manner similar to the construction of the machine shown and described in another application filed by me 95 March 7, 1895, Serial No. 540,849, to which reference may be had.

In so far as possible I shall in the following description designate the various parts by letters and figures like those designating 100 similar or corresponding parts in my said application, this invention being an improvement upon that shown and described in my said application.

Referring to the drawings, the frame of the machine comprises suitable uprights a , a , joined at proper intervals by the horizontal members a' , shown as and preferably formed from sheet metal bent into angular form.

The individual-registering keys are shown at b , b , arranged, preferably, in vertical series, each series being supposed to represent the candidates of as many different parties. 10 These registering-keys b are suitably mounted to slide in the frame, and (see Fig. 4) the shanks b^2 of the several keys at or near their inner ends are provided with suitable shoulders b^3 , which coöperate, respectively, with 15 suitable bell-crank or other levers c^2 , pivoted upon horizontal shafts c^3 and having their rearwardly-extended arms c^4 adapted to engage the bars b^4 and through the same move the actuators c' of the counters c of any desired construction, of which there is one for 20 each registering-key of the machine, excepting the independent-voting device or key.

Referring to Fig. 2, showing the rear side of the machine, it will be seen that each lever c^2 is mounted upon a long hub extending for 25 the entire width of its vertical series, as shown, and I have provided the hubs of the several keys with additional arms c^5 , upon which rest the vertically-sliding rods or bars c^6 , one for each arm c^5 , the said vertically-sliding bars moving in suitable guides c^6 on the frame and pointed or beveled at their upper ends to enter and separate the several interlocking devices c^7 , shown as arranged in a 30 single series for the entire machine and also shown as pivoted at c^8 and depending one in contact with another and with their free ends beveled or pointed, as shown.

In the normal condition of the machine any 35 one of the individual-keys may be pushed inwardly and through its bell-crank lever c^2 raise its vertically-sliding rod c^6 , causing the upper end of the latter to enter between two of the interlocking devices and separate the 40 same, and thereby move in opposite directions all of the interlocking devices at its opposite sides, so that while any single sliding bar c^6 , which I shall hereinafter designate as a "separator," is in its elevated position by reason 45 of the operation of any single key no other key can be operated, it being impossible to raise any other vertically-sliding bar or separator, for any other bar or separator when raised will contact with an interlocking device above it, which cannot be moved to one side because of the previous raising of another bar or separator.

Inasmuch as in the machine shown I have employed a single series of interlocking devices 50 for the entire machine, it will be evident that as one separator only can be raised at a time it is impossible to operate simultaneously any two or more registering-keys, whether in the same or different series.

55 In the present instance of my invention I have recessed the several separators c^6 at the rear side of the machine and, as indicated at

c^9 , Fig. 4, to receive the horizontal gravity-bar c^{10} , provided at its ends with inwardly-extended arms c^{11} , fast upon a horizontal shaft c^{12} , journaled in suitable bearings in the frame. Whenever any separator is raised, it also raises this gravity-bar c^{10} , the weight of which when the key is released acts to depress or return the said separator to its normal position, this one gravity-bar serving to return to their normal positions after operation all of the separators and keys of the machine.

The counters c are so constructed that when their actuators c' are elevated they will remain in their elevated positions until positively returned by operation of the resetting mechanism, so that should any single key be operated a succession of times only one— 85 the first—operation will be registered by the counter.

The resetting-shaft h^2 is shown in Figs. 2 and 4 journaled in suitable bearings in the frame and is provided above the several series 90 of counters c with rearwardly-extended arms h^2 , to which are jointed the upper ends of the resetting bars or rods h^3 , which depend, respectively, back of the counter-actuators in the series beneath and are provided with 95 pins h^4 , one pin for and above each counter-actuator, so that when the resetting-shaft is rotated the bars h^3 will be depressed, causing their several pins h^4 to act upon the several counter-actuators and return the latter 100 to their lowermost or normal positions ready for the next voter.

Referring now to Fig. 7, I have provided the shank of each registering-key with a beveled side lug b^6 , which engages one of the side 105 walls of a notch in the horizontally-sliding interlocking bar or member d , there being one such bar d for each horizontal row or series of registering-keys.

Whenever any single registering-key is 110 pushed inwardly to register a vote, its inclined lug b^6 acts to throw the horizontally-sliding bar d for that horizontal series to the left, Fig. 1, said bar being returned again to its normal position to the right by a suitable 115 spring b^7 .

At the extreme left-hand end of the machine I have provided a series of studs m^1 , upon which I may pivot the locking-levers m , weighted at one (herein their right-hand) end 120 and adapted to drop upon the upper edges of the horizontal sliding bars d beneath and to engage notches m^2 therein. The left-hand ends of these locking-levers m are notched, as at m^3 , for engagement by suitable lugs m^4 125 on the levers m^5 , pivoted at m^6 and weighted at m^7 to cause them to normally assume their positions shown in all but the lowermost lever in Fig. 1.

When any of the horizontal sliding bars d 130 is moved to the left by operation of any key in its horizontal series, the end of said bar strikes the lower end of the lever m^5 in line with it and throws the upper end m^4 of said

lever to the right over and into the notch in the end m^3 of the lever m , permitting the opposite weighted end of said lever m to drop upon the upper edge of the horizontal slide-bar d to engage the notch m^2 therein and prevent a second movement of the said slide-bar in the same direction, thus preventing successive operation of the keys in any single horizontal series, simultaneous operation of the said keys being prevented by the interlocking devices referred to.

The resetting-shaft h^{25} is provided with a lever m^8 , depending from which is a rod or bar m^9 , extending back of the several weighted levers m , and provided beneath each one with a pin m^{10} , so that when the said resetting-shaft is moved to reset the machine the several pins m^{10} will engage the levers m at their under sides and lift such as are in engagement with and locking against movement the slide-bars d out of engagement with said slide-bars and permitting the weighted levers m^5 to drop back into their positions shown in Fig. 1 to hold the said levers m in their elevated positions until again released by another operation of their respective slide-bars.

To group any desired number of the keys to enable any voter to vote for a plurality of candidates for the same office—as, for instance, a plurality of candidates for the office of school-board—I have provided the grouping devices II II much like the grouping devices shown in my previous application referred to, and which are herein constructed as follows, it being necessary to describe but a single device, it being understood that the others are similar: Upon the frame is provided a projecting stud h , Fig. 8, upon which is loosely mounted the hub h^1 of a ratchet-toothed wheel h^2 , the said hub at its inner end having fast upon it a pulley h^{13} , about which is passed a cord h^{24X} , to which is suspended a weight h^{15} . The ratchet-wheel h^2 receives a step-by-step movement from a pawl h^4 , pivoted at h^5 upon the actuator h^6 , having its hub h^7 loosely journaled about the hub h^1 of the said ratchet-wheel, a spring h^9 holding the said pawl normally in engagement with the teeth of the ratchet. At the front of the ratchet-wheel h^2 is a disk h^{10} , provided with a hole for the reception of a screw 9 , which latter is adapted to enter any one of the circular series of threaded holes 10 (see Fig. 10) in the outer face of the ratchet-wheel h^2 , said disk h^{10} being shown as provided with a peripheral lug h^{11} , which at a predetermined time contacts with a suitable stop h^{12} on the frame to prevent further rotation of the ratchet-wheel.

The actuator h^6 , to which the pawl is attached, has pivoted to it at h^8 the group-actuating bar e , which depends back of the several horizontal slide-bars d , said bar e being provided with suitable shoulders for engagement of the bell-crank levers f , pivoted upon the studs f' on the frame and having

their other arms engaging notches d^X in the slide-bars d . Any of these bell-crank levers f may be removed at will, and by the use of these I can connect any horizontal bar d with any vertical counter-bar e , and thus connect any horizontal series of keys with any group-counter.

It is evident that the sliding movement of a bar d will rock the bell-crank lever f connected with it and cause the connected counter-bar e to be raised and through the pawl h^4 rotate the ratchet-wheel of that counter one tooth.

The number of times which any single horizontal bar d or, in fact, the number of times which any bar d , connected with any single group-counter, may be operated, and therefore the number of keys in the series represented by those bars which may be operated, is determined by the position of the stop h^{11} of that counter, which when it brings up against the fixed stop h^{12} on the frame prevents further movement of the group-counter and also prevents further operation of any of the keys connected with that group-counter.

A suitable back pawl h^{12X} is provided to prevent retrograde movement of the ratchet-wheel h^2 .

The resetting-shaft h^{25} is provided with an arm h^{21} , Fig. 1, which engages one arm of a bell-crank lever h^{23} , pivoted at h^{22} , and has its other arm h^{21} engaging the horizontally-moving bar h^{20} , connected at each group-counter with a pin h^{18} on a cam-plate h^{16} , loosely journaled upon the hub h^7 of the counter-actuator, and which when rotated by movement of the resetting-shaft operates to lift both pawls from engagement with the ratchet-wheel h^2 and permit the weight h^{15} at the back of the machine to return the said ratchet-wheel to its normal starting position in readiness for a new voter.

When any single horizontal series of keys is to be operated entirely by itself independent of any grouping device, its sliding bar d is locked by devices m and m^5 upon operation of one key to prevent subsequent operation of any other of the keys in the same series; but when any two or more horizontal series of keys are grouped together to enable a large number of candidates to receive votes for the same office, as in the instance referred to, their sliding bars d must be permitted to return after each operation of a key to their normal positions in order that the voter, if he so chooses, may cast his second or third vote for another candidate whose name appears in the same horizontal series, and therefore when any two or more series are grouped together—that is, connected with any of the grouping-counters—the levers m for those horizontal series are temporarily removed and the group-counter II relied upon to limit or fix the whole number of keys operated.

Referring now to Fig. 1, I have provided each vertical series of individual-registering

keys with a straight-ticket key b' , as in my previous application, these straight - ticket keys when operated registering at a single movement one vote for all the candidates represented by all the keys in the same vertical series beneath it, but independent—i. e., without operation—of said other keys.

Referring now to Fig. 4, the shanks b^2 of the straight-ticket keys b' are provided at 10 their inner ends with lugs or shoulders b^{10} , which engage depending arms of the bell-crank levers b^{11} , pivoted upon a horizontal shaft b^{12} and having their other arms connected at b^{13} with the vertically-movable bars 15 b^{14} , which depend back of the counter-actuators, (see Fig. 2,) one such bar for each vertical series of counters, and are provided with pins b^{15} beneath the several actuators in the adjacent series, whereby operation of any 20 straight-ticket key will operate to lift the vertically-movable bar b^{14} , connected therewith, and cause its several pins b^{15} to simultaneously act upon and raise the actuators of all the counters in that vertical series, thereby 25 simultaneously registering one vote for all the candidates represented by those counters and by the vertical series of individual-keys beneath the straight - ticket key operated. The shanks b^2 of the straight-ticket keys b' 30 are also provided with other lugs or shoulders b^{16} , which upon operation of the keys act upon the depending arms b^{17} , fast on a horizontal shaft b^{18} , journaled in suitable bearings in the frame and provided at the right end of 35 the machine in Fig. 2 with the arms b^{19} , which curve upwardly and over to the tops of the several group-counters, (see Fig. 3,) the pulleys h^{18} of the several group-counters being provided with notches b^{20} , which in the normal position of the machine before any votes 40 are cast are in position directly beneath these curved arms.

If any individual-key connected with a grouping device has been operated, that 45 grouping device will have been moved one notch of its ratchet-wheel, thereby carrying the notch b^{20} referred to out of register with the overhanging arm b^{19} , so that it is afterward impossible to operate any of the straight-ticket keys, because the overhanging arm 50 above the counter operated will upon attempted movement of the straight - ticket shaft b^{18} contact with the periphery of the pulley h^{18} of that group-counter.

If none of the individual-keys have been 55 operated, then any straight-ticket key may be operated, the several overhanging arms h^{19} descending into the notches b^{20} of the group-counters.

Referring to Fig. 1, it will be understood 60 that the horizontal slide-bar d for the horizontal series of straight-ticket keys has no spring to return it after each operation.

Referring to Fig. 15, showing two of the 65 straight-ticket keys, each key is provided with a bevel-lug b^6 at one side and at its opposite side with an additional square-faced

lug b^{7X} . Its square lug b^{7X} first passes through the notch in the slide-bar d and immediately thereafter the bevel-lug b^6 acts upon and 70 throws the said slide-bar to the left behind the lug b^{7X} to prevent return of the key operated to its normal position, thereby holding its separator c^6 in its elevated position, separating the interlocking devices c^7 and preventing subsequent operation of any other key in the machine.

To prevent operation of any straight-ticket key after operation of any individual-key not included in any group, I have provided a 80 vertically-sliding bar b^{23} , (see Fig. 1,) jointed at its upper end to an arm b^{24X} , fast on the straight-ticket shaft b^{18} and provided with a series of pins b^{24} , arranged, respectively, below and out of the path of movement of the several horizontal slide-bars d .

It is impossible to operate a straight-ticket key without depressing the slide-bar b^{23} , and when any slide-bar d has been moved to the left by operation of any single individual-key it will at once strike the upper end m^4 of the lever m^5 in its abnormal position into which it was moved by previous movement of the said slide-bar and in which it is held by the weighted lever m , so that movement of 95 the said slide-bar b^{23} and of any of the straight-ticket keys is prevented. It will thus be seen that the interlocking devices c^7 prevent simultaneous operation of any two keys of the machine, that the operation of any single individual key prevents subsequent operation of any straight-ticket key by reason of the movement of one of the levers m^5 beneath a pin on the vertical slide-rod b^{23} , and that operation of any straight-ticket key, it remaining in its inmost position with its separator in position separating the locking devices, prevents subsequent operation of any individual-key, so that the keys of the entire machine are properly interlocked to effectually prevent any repeating or illegal voting.

Any straight-ticket key when operated and held in its inmost position is returned to its normal position when the machine is reset by means of a small bell-crank lever m^{11} , Fig. 1, pivoted at m^{12} and adapted to be moved by one of the pins m^{10} on the rod m^9 , connected with and moved by the resetting-shaft, said lever m^{11} when moved acting to positively return the slide-bar d of the horizontal straight-ticket series to its normal position, releasing the key operated and permitting it under the action of the weight of the gravity-bar c^{10} to be returned to its normal position.

Referring now to Figs. 2, 5, and 6, I will proceed to describe the particular independent-voting mechanism which I have herein provided.

Referring particularly to Fig. 5, w is the independent-voting key, it being constructed 130 and operating precisely as the other keys of the machine and provided with its vertically-movable separator c^6 , coöperating with the interlocking devices as the other keys, which

renders it impossible to simultaneously operate it and any of the other keys and impossible to operate it after operation of any straight-ticket key. While I have herein shown this independent-voting key as in the same horizontal series with the straight-ticket keys, it is not, however, connected in any manner with the horizontal slide-bar *d* of the straight-ticket series, nor is it in any wise connected with the straight-ticket mechanism. Upon this independent key *w* I have mounted an inclined receiver *w'*, provided with a suitable slot *w*² for the reception of the independent ballot, a pair of springs *w*³ holding the ballot frictionally in position when deposited in the receiver. Immediately over this inclined receiver is a table *w*¹³, provided with openings for the reception of the ejector-arms *w*⁹, fast on a shaft *w*⁸, journaled in suitable bearings in the frame and connected by a link *w*¹¹ with an arm *w*¹⁰ on the resetting-shaft *h*²⁵ of the machine. The voter having cast his votes by means of the individual-registering keys for such candidates as are represented by said keys wishing to vote for candidates whose names do not appear at the face of the machine writes the names of such irregular or independent candidates upon a proper ballot provided for him and deposits said ballot in the inclined receiver *w'*. He then operates the independent-registering key *w* and pushes the receiver inwardly beneath the table *w*¹³, which prevents subsequent access to the receiver for tampering with the ballot, such movement of the independent-key raising its separator between two of the interlocking devices. The key remains locked in position with its receiver concealed beneath the table *w*¹³ by means of a lug *w*²⁰ on the under side of the key and shown in dotted lines, Fig. 5, which passes over an inturned arm on the pivoted lever *w*²¹, which, acted upon by a spring *w*²², springs upwardly in front of the lug and holds the key in its inmost position. When the voter leaves the booth and the resetting-shaft is operated in suitable manner—as, for instance, such as shown in my said application—the ejector-arms *w*⁹ are depressed, they engaging and positively ejecting from the receiver the ballot placed therein, such ballot being deposited in a suitable receptacle provided for it below. In the downward movement of the ejector after the ballot has been ejected from the receiver a lug *w*²³ on one of the ejector-arms strikes the lever *w*²¹ and depresses the same to release the key *w* and permit the latter to be returned to its normal position by a spring *w*²⁴, attached to its separator.

It is necessary to provide some means of informing the persons who count the ballots of the number of votes which any voter has regularly cast through the keys of the machine before using the independent-voting device in order that it may be known that he does not vote for the entire number of can-

didates allowed him and then vote for additional candidates through the medium of the independent device. To accomplish this, I have provided a number-indicating device, shown as a type-wheel *l*, pivoted at *l*¹ in a pair of arms *l*², in turn pivoted at *l*³ and extended at *l*⁴, (shown in the broken portion of Fig 5,) bracketed thereto and at their lower ends *l*⁵ contacting with suitable adjustable stops *l*⁶, springs *l*⁷ acting to draw the said lower ends *l*⁴ to the right, Fig. 5, to throw the upper ends and the type-wheel to the left, Fig. 5. The levers *l*² carry a suitably-arranged type-ribbon *l*⁷, which stands in front of the type upon the wheel. The type-wheel is rotated by means of a pawl *l*⁸, pivoted upon a suitable pawl-carrier *l*⁹, which is provided with a pin *l*¹⁰, shown in dotted lines, Fig. 5, as entering the forked end of an arm *l*¹¹, fast on the shaft *c*¹², to which the gravity-bar *c*¹⁰ is attached. Whenever an individual-registering key is operated, the gravity-bar is raised, as described, causing its arm *l*¹¹ to be depressed, and thereby through the pawl *l*⁸ rotate the numbering-wheel one tooth or number, and thus each operation of an individual-key feeds the numbering-wheel one number or tooth, so that the number of keys operated is always indicated by the particular type which is fed into position facing the independent ballot in the independent-ballot receiver. When the voter subsequently pushes in the independent-key *w* to deposit an independent ballot, the ballot in the receiver moved by the key is by movement of the key pushed against the type of the type-wheel brought into position by previous operation of the registering-keys, which type impresses upon the independent ballot a number to show to the person counting the ballots how many votes the voter had cast before availing himself of the independent ballot. Thus if any voter is permitted to vote for twelve different candidates and votes for nine he is entitled to place the names of three candidates upon an independent ballot and deposit it, as described, the figure "9," however, being impressed upon that ballot by the number-indicating mechanism described to show to the person counting the ballots that he has, all told, cast only the number of votes allowed him. Having cast his nine votes by means of the registering-keys, should he attempt to cast four or more upon the independent ballot the figure "9," appearing upon the ballot, together with the four or more names, will show to the person counting the ballots that the voter has cast more votes than was allowed him, and his independent ballot is cast aside.

Instead of indicating upon the independent ballot the number of votes previously cast by the voter through the registering-keys, I may, by a simple reversal of the order of the figures, print upon the independent ballot a figure showing the number of ballots which he may yet cast through the independent

device if he so desires, the mechanism being precisely the same, requiring simply the reversal of the order in which the type are arranged upon the type-wheel.

5 When the gravity-bar c^{10} drops after the operation of any single key, it automatically returns the pawl l^8 to its position preparatory to feeding the type-wheel a second step, and when the independent ballot is pressed 10 against the printing-wheel the latter, by means of the pivot l^9 and the spring l^{16} , yields in front of the moving ballot in order that a firm, yet yielding, impression may be made. A back pawl l^{12} is provided to prevent retrograde movement of the type-wheel.

15 To restore the number-indicating mechanism to its normal position in readiness for a new voter, I have provided a cam-plate l^{13} , (shown separately in Fig. 14,) which when 20 rotated lifts both the pawls l^8 and l^{12} out of engagement with the ratchet-wheel of the device. This disengaging-cam l^{13} is connected by a link l^{14} with one of the ejector-arms w^9 , so that movement of the resetting-shaft acts 25 through the ejector-arms to rotate the disengaging-cam l^{13} sufficiently to disengage the pawls and permits the spring l^{15} , acting through a cord l^{16} , wound upon a pulley l^{17} on the type-wheel shaft, to return the type-wheel to its normal position, where it is stopped 30 by a stop l^{18} coming into contact with one of the levers l^2 .

It is desirable that some means be provided for indicating to the voter that his votes have 35 been properly cast by his operation of the various keys and also to indicate to him at any time the particular candidate for whom he has already voted, to prevent his becoming confused. For this purpose I have provided 40 adjacent the several keys of the machine suitable visual indicators s^5 , (shown in Fig. 16,) as suitably-shaped plates s^5 on the ends of suitable arms fast on shafts s^6 , journaled in suitable bearings in the machine-frame, said shafts within the machine being 45 provided with suitable locking-arms s^7 , adapted to be engaged by suitable shoulders s^8 on levers s^9 , suitably pivoted at s^6 , the said levers s^9 acting as pawls or locking devices 50 coöperating with the arms s^7 to hold the indicators s^5 normally in their vertical positions concealed behind suitable shields s^{11} , secured to the face-plate of the machine. When 55 these levers s^9 are raised, the arms s^7 are released, and the indicators s^5 under the action of gravity drop into their horizontal exposed positions, as shown at 25, Fig. 1. In the present instance of my invention the levers s^9 at their free ends rest upon the tops of the 60 several shanks of the registering-keys, said shanks being provided, as shown, with suitable inclined lugs s^{12} , which when the respective keys are pushed in raise the levers s^9 , resting upon the said keys, and thereby release the 65 corresponding indicators, which drop and indicate to the voter that he has registered the votes corresponding to the keys operated.

The inclined lugs s^{12} are so located on the registering-keys that they will not act upon and raise the levers s^9 to drop the indicators until their keys have been sufficiently moved to register a vote by operation of their respective counters. After the indicators have been dropped they are all restored again to their concealed positions by means of arms s^{13} on the resetting-shaft h^{25} , to which arms are jointed rods s^{14} , passing down beside the vertical series of keys and provided each with a series of pins s^{15} , projecting beneath the ends of the levers s^9 , so that when the resetting-shaft is rotated to reset the machine these rods s^{14} are raised to thereby, through their pins s^{15} , turn the indicators into their vertical concealed positions, where they are caught and locked by the locking-levers s^7 .

So far as known to me I am the first to provide in a voting-machine suitable interlocking mechanism to prevent simultaneous operation of any two or more keys in the same or different series, whether the same are connected in groups or operated each series independently of the others, and I am also the first, so far as known to me, to employ in a voting-machine a single interlocking mechanism capable of being connected with and to control the operation of all the keys in any one or more series. So far as known to me I am also the first to provide the several keys in a voting-machine with visual indicating devices adapted to be moved by operation of their respective registering-keys to indicate to the voter that he has cast his vote or has so operated the key as to register a vote and to indicate to the voter the particular candidates for whom he has voted.

So far as known to me I am the first to use a single independent-voting device for the entire machine and to provide in connection therewith mechanism to indicate upon any independent ballot cast the number of candidates for whom any voter is entitled to cast his vote upon said independent ballot, whether such number is indicated by the number of votes previously cast or by the number remaining to be cast, if he so desires. I therefore consider myself entitled to claim the above features in a voting-machine broadly and with the other features of my invention hereinbefore specifically described without limitation as to constructional arrangements and details.

I claim—

1. In a voting-machine two or more series of registering-keys, arranged in different lines and comprising all the registering-keys in the machine, a single series of interlocking devices and separators connected respectively with and actuated by the said keys to separate said interlocking devices to prevent simultaneous operation of the separators of any two or more keys in the same or different series, means to automatically withdraw said separators from between said interlocking devices after each operation of their respective keys, counters

for the respective keys, a resetting mechanism, and means to prevent a plurality of operations of said counters by their keys between any two succeeding operations of said resetting mechanism, substantially as described.

2. In a voting-machine; a plurality of series of registering-keys; a slide-bar for each of said series, the same adapted to be reciprocated by a full inward and return movement of any one of the said keys in each series; a locking device coöperating with and to prevent successive reciprocations of any one of said slide-bars between successive operations of the resetting mechanism, means to prevent simultaneous operation of two or more slide-bars and the resetting mechanism connected with and to release the locking device, substantially as described.

20 3. In a voting-machine; a series of registering-keys; one or more straight-ticket keys operable without operation of said registering-keys; a slide-bar adapted to be moved by operation of any of the registering-keys; a locking device therefor; a coöperating holding device for the said locking device; and means coöperating with said locking and holding devices to prevent operation of the said straight-ticket keys subsequent to operation of any of said registering-keys, and a resetting mechanism, substantially as described.

25 4. In a voting-machine, two or more series of registering-keys, one or more straight-ticket keys, a slide-bar for each series of registering-keys adapted to be moved by operation of any of the registering-keys in its respective series, locking devices for the respective bars, coöperating holding devices and means coöperating with said locking and holding devices to prevent operation of a straight-ticket key subsequent to operation of any registering-key, and a resetting mechanism, substantially as described.

30 5. In a voting-machine, the combination with a plurality of registering-keys and separate counters for said keys, of a visual indicator for and adapted to be moved by operation of each of said keys to indicate proper operative movement of the said keys and also to indicate to the voter, at any time, the candidate for whom he has voted, substantially as described.

35 6. In a voting-machine, the combination with one or more registering-keys separate counters for said keys, visual indicators for the respective registering-keys and adapted to be moved by operation of the said keys to indicate to the voter, at a glance, the particular candidate for whom he has voted, and a resetting mechanism connected with and adapted on operation to return said visual indicators to their original positions, substantially as described.

40 7. In a voting-machine, the combination with one or more series of registering-keys, of an independent-voting device containing an independent-ballot receiver; a number-indi-

cating device and means operated by movement of the registering key or keys to cause movement of the said number-indicating device to indicate the number of candidates for whom the voter is entitled to cast his vote by means of said independent ballot, substantially as described.

45 8. In a voting-machine, the combination with one or more series of registering-keys, of an independent-voting device containing a ballot-receiver, a printing device operated by movement of the said registering-keys, and means to impart to the said printing device and ballot-receiver a relative movement to cause the former to print upon the independent ballot in the said receiver a character indicating the number of independent votes any voter is entitled to cast, substantially as described.

50 9. In a voting-machine, the combination with two or more series of registering-keys, said series being arranged and operating in different planes, of a single movable bar, connecting devices interposed between the same and the respective keys whereby operation of any single key acts to move said bar from normal into abnormal position, said bar by its return to normal position acting to return 95 said key to its normal position, whereby said bar is successively moved by successive operation of the keys from normal into abnormal position and each time acts to return the key which moved it, to its normal position, substantially as described.

55 10. In a voting-machine, the combination with a series of registering-keys and a movable bar adapted to be moved from normal into abnormal position by any one of a plurality of said keys, an independent-voting device, a number-indicating device coöperating therewith, and connections between said movable bar and number-indicating device whereby successive movements of the said bar automatically move said number-indicating device into position to indicate upon the ballot the number of independent votes previously registered by any single voter, substantially as described.

60 11. In a voting-machine, two or more series of registering-keys, counters therefor, means to automatically return said keys to their normal positions after each operation; a single interlocking mechanism to prevent simultaneous operation of any two or more keys in the same or different series, a straight-ticket key also coöperating with said interlocking mechanism and interlocked thereby with all the series of registering-keys, and adapted 125 when operated to remain in the position into which it is moved, to thereby, through said interlocking mechanism, prevent subsequent operation of the remaining registering-keys, and a resetting device to operate, substantially as described.

65 12. In a voting-machine, the combination with a plurality of registering-keys and separate counters for said keys, of a normally-

concealed visual indicator, and means operated by movement of said keys to expose the respective indicators to indicate, visually, proper operative movement of said keys, and
5 also to indicate to the voter at any time the candidate or candidates for whom he has voted, substantially as described.

In testimony whereof I have signed my name to this specification in the presence of two subscribing witnesses.

ALBERT SNOECK.
